UNITED STATES PATENT OFFICE

95,965

DESIGN FOR A GLASS BOTTLE

Lawrence J. Kihm, Pittsburgh, Pa., assignor to J. T. & A. Hamilton Company, a corporation of Pennsylvania

Application October 16, 1934, Serial No. 53,633

Term of patent 3½ years

To all whom it may concern:

Be it known that I, Lawrence J. Kihm, a citizen of the United States, residing in Pittsburgh, in the county of Allegheny and State of Pennsylvania,
have invented a new, original, and ornamental Design for a Glass Bottle, of which the following is a specification, reference being had to the accompanying drawing, forming part thereof.

In the drawing: Fig. I is a side elevation of a glass bottle showing my new design; and Fig. II is a plan view of the glass bottle.

It will be noted that Fig. I of the drawing shows
a panel effect on the presented face of the bottle.
This panel effect may be repeated upon other of the side faces of the bottle.

I claim:

The ornamental design for a glass bottle, substantially as shown and described.

LAWRENCE J. KIHN.
